UNITED STATES PATENT OFFICE.

BENOIT ORIOL, OF ST. CHAMOND, FRANCE.

BOBBIN-CARRIER FOR BRAIDING-MACHINES.

SPECIFICATION forming part of Letters Patent No. 415,311, dated November 19, 1889.

Application filed July 5, 1888. Serial No. 279,120. (No model.)

To all whom it may concern:

Be it known that I, BENOIT ORIOL, a citizen of the Republic of France, and a resident of St. Chamond, in the Department of Loire, 5 French Republic, have invented certain new and useful Improvements in Bobbin-Carriers for Braiding-Machines, of which the following is a specification.

My invention relates to improvements in 10 bobbin-carriers for braiding-machines; and the object of the same is to secure a regular unwinding of the thread from the bobbin when the machine is running at high speed, and consequently to increase the output of 15 the braiding-machine.

The bobbin-carriers heretofore made are limited to a certain speed, which cannot be exceeded on account of the resistance caused by the friction between the bobbin and the 20 bobbin-carrier and the danger of breaking the thread as often as the limited speed is surpassed. In order to meet such difficulty, the bobbin should be made to facilitate the delivery of the thread as soon as a certain 25 tension of the thread is reached. I attain this object by the mechanism illustrated in the accompanying drawings, in which—

Figure 1 is a side view of the bobbin-carrier with the bobbin; Fig. 2, a back view, and 30 Fig. 3 a top view of the same; while Fig. 4 represents three different views of a detail hereinafter referred to.

Similar letters refer to similar parts throughout the several views.

35 The lever L, controlling the rotation of the bobbin upon the hollow bobbin-carrier, is pivoted at a to the upright arm n, attached to the said carrier, and engages the screw-thread of a collar D, resting upon and secured to 40 the top of the bobbin B. As soon as the bobbin-thread f commences to elevate the tension-weight p, and the tension of the thread exceeds a certain limit, the arm e of the usual catch-lever E tends to turn the regulating-lever L into the position illustrated by the dotted line z. By this movement the point of the regulating-lever L acts upon the screw-threads of the collar D, the pitch of the screw-thread corresponding with that of the teeth 45 C of the collar, and thus causing the latter to 50 C of the collar, and thus causing the latter to turn with the bobbin in the direction of the

unwinding of the thread. Herefrom it results that the whole resistance the bobbin offers to the rotation ceases at the moment where usually it would be the greatest, and 55 this result is effected without causing the thread to overcome a force capable of breaking it, in order to cause the play of the regulating-lever, which then occupies its original position, while the catch-lever drops again. 60 At this instant the regulating-lever L cannot turn the bobbin backward, because its point rides upon the upper face of the screw-threads of the collar D, until it meets a groove of the thread, which will allow the 65 lever L to drop into position to again act upon the collar D and the bobbin B when the tension of the bobbin-thread again exceeds the limits of the desired tension.

Another reason of the resistance of the 70 bobbin to its proper rotation is caused by the circumstance that the thread is not drawn off perpendicularly from the bobbin. To effect this, a weighted thread-guide G, guided in its reciprocations by its projection t, within the 75 vertical slot of the upright arm n within the bow m, is carried by the thread f of the bobbin to that position where the thread is drawn off perpendicularly to the axis of the bobbin. The thread passes direct from the bobbin B, 80 through the slot u, around the stay i in the sliding thread-guide G, thence upward through the eye in the top of the upright arm n, downward through an eye in the catch-lever E, thence through an eye in the upper 85 end of the tension-rod p and up through the eye in the top of the bobbin-carrier. The weight of the sliding thread-guide G is such as to maintain the thread always at right angles to the bobbin while unwinding, thus 90 insuring a more smooth and uniform unwinding of the thread from off the bobbin.

As all other parts of the bobbin-carrier and their action are generally known, they do not require further explanation, inasmuch as they 95 do not form essential features to carry my invention into effect. I therefore do not claim the construction of the bobbin-carrier, broadly; but

What I do claim, and desire to protect by 100 Letters Patent, is—

In a bobbin-carrier for braiding-machines,

the combination of the bobbin B, the collar D, formed with screw-threads, the regulating-lever L, pivoted to the upright arm *n* of the bobbin-carrier, and the double-armed catch-lever E, substantially as and for the purpose specified.

5 In testimony that I claim the foregoing as my

invention I have signed my name, in presence of two witnesses, this 16th day of April, 1888.

BENOIT ORIOL.
